UNITED STATES PATENT OFFICE

2,479,316

AIRPLANE PICKUP DEVICE

John H. Connelly, Phoenix, Ariz., assignor to
 Southwest Airways Company, a corporation of
 Arizona

Application October 20, 1944, Serial No. 559,545

12 Claims. (Cl. 258—1.2)

1

This invention relates to a pick-up device for airplanes, and more particularly to such a device adapted to pick up an article or articles from a stationary position, as on the ground, from a moving airplane while in flight.

A primary object of this invention is the provision of an improved pick-up device characterized by resistance means, whereby the article to be picked up will be relatively gradually accelerated to the flying speed of the plane.

An additional object of this invention is the provision of such a device which will serve to minimize the shock otherwise transmitted to the article and/or plane at the instant of pick-up contact.

Still another object is the provision of such a device provided with means for progressively increasing the resistance of the shock-absorbing means in such a device, as the speed of the picked-up article increases.

A still further object is the provision of such a device, including a cable adapted to be payed out to pick up an article from a stationary position, having hydraulic means in association therewith, whereby when the article is picked up, the cable will continue to be payed out, against increasing resistance from the hydraulic means, until such time as the article so picked up has achieved a speed equal to the flying speed of the plane.

Still another object is the provision of such means which may, upon the achievement of flying speed of the article picked up, be utilized to draw the article into the body of the plane.

A still further object is the provision of means in association with such a device whereby the cable may be reeled and unreeled without actuation of the above-mentioned hydraulic mechanism.

Still another specific object is the provision, in such a device, of means whereby sudden shock to the hydraulic mechanism, such as may be occasioned by quick pick-up of an article, is eliminated.

Other objects reside in the combinations of elements, arrangements of parts, and features of construction, all as will be more fully pointed out hereinafter and disclosed in the accompanying drawings, wherein there is shown a preferred embodiment of this inventive concept.

In the drawings:

Figure 1 is a partially schematic elevational view of an airplane in flight, equipped with the mechanism of the instant invention, about to pick up an article from the ground.

Figure 2 is a side elevational view of the mecha-

nism incorporated within the plane, adapted to control the pick-up of the article on the ground.

Figure 3 is a sectional view taken substantially along the line 3—3 of Figure 2, and

Figure 4 is a sectional view taken substantially on the line 4—4 of Figure 2, as viewed in the direction indicated by the arrows.

Like reference numerals refer to like parts throughout the several views of the drawings.

Having reference now to the drawings, and more particularly to Figure 1, there is generally indicated at 10 an airplane in flight, through a suitable aperture 15 in the base of which extends a cable 11 provided at its extremity with a grappling hook 12. Hook 12 is adapted to engage with any desired stationary article 13 positioned on a suitable ground pick-up device, as, for example, suspended on a cord positioned between two posts 14.

20 As best shown in Figure 2, the cable 11 extends through the aperture 15 in the floor 16 of the plane to a reel generally indicated at 17, comprised of end plates 18 and 19 and a central core 20. Reel 17 is mounted on an axle 21, the extremities of which are journaled in suitable journals or bearings in uprights 22 and 23, mounted on a base plate 24 secured to the floor 16 of plane 10.

25 Positioned adjacent plate 18 is a clutch face 25 adapted to engage and abut an opposed clutch face 26 associated with a gear 27 which is threadedly mounted on a threaded portion 28 of axle 21. Gear 27 is adapted to engage with a gear 30 mounted on a drive shaft 31 of a hydraulic pump 32, of any desired conventional type, the opposite end of shaft 31 being journaled in a suitable supporting bracket 33.

Cut into the core 20 of reel 17, at the side adjacent plate 19, is a conical depression 35 adapted to be engaged by a cone clutch 36 splined, as by splines 37, to axle 21. A threaded sleeve 38 is adapted to engage in a threaded bore 39 in support 23, and has integral therewith or secured thereto a hand wheel 40, the sleeve and hand wheel being adapted to rotate about axle 21, which is slidably fitted therein, whereby rotation of the same will force cone clutch 36 into engagement with conical depression 35 for a purpose to be described hereinafter.

40 From the foregoing it will be seen that, since the reel 17 is, in the absence of one of the clutch engagements previously mentioned, free to rotate on shaft 21, it may be rotated by hand, in such manner as to pay out the cable or rope 11 when it is desired to utilize the same for picking up an

55

article from the ground or the like. When a sufficient amount of cable has been payed out, the hand wheel 40 is turned to cause the clutch 36 to seat in the conical depression 35 so that when the grappling hook 12 engages the article to be picked up 13, the resistance of the article 13 to movement occasions the further unrolling of the cable 11 from reel 17, which in turn rotates the axle 21 and causes the threaded gear 27 to move along the threaded portion 28 until the clutch faces 25 and 26 engage. Such engagement occasions rotation of the gear 27 which in turn rotates gear 30, shaft 31 and hence drives hydraulic pump 32.

Referring back to Figure 1, an inlet line 50 leads from a reservoir 51 of hydraulic fluid or the like to hydraulic pump 32, and an outlet 52 leads therefrom to an accumulator 53. Accumulator 53 is of conventional design and comprised of two halves 54 and 55 separated by a flexible diaphragm 56. Contained within half or portion 55 may be compressed air, or an inert gas under pressure, to counteract the increasing pressure of hydraulic fluid pumped through line 52 into portion 54 thereof. Thus, it will be seen that as the pressure in accumulator 53 is increased by the action of the pump 32, the force required to operate the pump will increase progressively, until such time as the article picked up has reached the speed of the flying plane, or before, at which time further paying out of the cable 11 by rotation of reel 17 will be precluded, due to the increased force necessary to force further fluid into the accumulator 53.

A second line 57 leads from storage tank 51 to a conventional hand pump 58 provided with an operating handle 59, from which a line 60 leads through a one-way valve 61 into accumulator 53.

After the article has reached flying speed and it is desired to draw the same upwardly into the plane through the opening 15 in the floor thereof, the hand pump 58 is operated by means of handle 59 until such time as the pressure in accumulator 53 is sufficiently great to drive hydraulic pump 32 in a reverse direction, whereupon the same acts as a hydraulic motor to wind the cable 11 about reel 17, rotating the reel in the opposite direction from that previously discussed, whereupon the cable and its attached article are drawn upwardly into the plane.

Upon the completion of such operation, when the article is safely aboard, and it is desired to re-set the device, a hand valve 62 positioned in a line 63 leading from accumulator 53 to storage tank 51 is opened permitting the fluid to drain from the accumulator back to the storage tank until such time as the pressure is equalized, whereupon the device is again ready for operation in the manner previously described.

A pressure gauge 64 is provided at any suitable location, as, for example, in line 63, to indicate at all times the pressure in accumulator 53.

Thus, from the foregoing it will be seen that there is herein provided a device accomplishing all the objects of this invention and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

1. In a device of the class described a reel

freely rotatable upon a shaft, manually controlled means to establish a driving connection between the reel and the shaft, hydraulic reel braking means adapted to offer progressively increasing resistance to the rotation of the reel including a pump and means operable upon rotation of the shaft to establish a driving connection between the reel and the pump.

2. In a device of the class described, a reel freely rotatable on a shaft, manually controlled means to establish a driving connection between the reel and the shaft, a pump, means operable upon rotation of the shaft to establish a driving connection between the reel and the pump and means coupled to the pump outlet to create a progressively increasing back pressure in the pump whereby progressively increasing resistance will be offered to the rotation of the reel.

3. In a device of the class described, a reel freely rotatable on a shaft, manually controlled means to establish a driving connection between the reel and the shaft, a pump, means operable upon rotation of the shaft to establish a driving connection between the reel and the pump and an accumulator coupled to the pump outlet to create a progressively increasing back pressure in the pump whereby progressively increasing resistance will be offered to the rotation of the reel.

4. In a device of the class described, a reel freely rotatable on a shaft, manually controlled means to establish a driving connection between the reel and the shaft, a pump, means operable upon rotation of the shaft to establish a driving connection between the reel and the pump, a source of fluid supply coupled to the intake side of the pump and an accumulator coupled to the outlet side of the pump to receive the fluid pumped by the pump and create a progressively increasing back pressure in the pump whereby progressively increasing resistance will be offered to the rotation of the reel.

5. In a device of the class described, a reel freely rotatable on a shaft, manually controlled means to establish a driving connection between the reel and the shaft, a pump, means operable upon rotation of the shaft to establish a driving connection between the reel and the pump, a source of fluid supply coupled to the intake side of the pump and an accumulator coupled to the outlet side of the pump to receive the fluid pumped by the pump and create a progressively increasing back pressure in the pump whereby progressively increasing resistance will be offered to the rotation of the reel and means to transfer the fluid pumped into the accumulator to the source of fluid supply.

6. In a device of the class described, a reel freely rotatable on a shaft, manually controlled means to establish a driving connection between the reel and the shaft, a pump, means operable upon rotation of the shaft to establish a driving connection between the reel and the pump, a source of fluid supply coupled to the intake side of the pump and an accumulator coupled to the outlet side of the pump to receive the fluid pumped by the pump and create a progressively increasing back pressure in the pump whereby progressively increasing resistance will be offered to the rotation of the reel and a pump between the accumulator and the source of fluid supply to transfer fluid from the accumulator to said source.

7. In a device of the class described, a reel freely rotatable upon a shaft, manually controlled means to establish a driving connection between the reel and the shaft, hydraulic reel braking

means adapted to offer progressively increasing resistance to the rotation of the reel including a pump and means operable upon rotation of the shaft to establish a driving connection between the reel and the pump, a cable attached at one end to the reel and a grappling hook attached to the opposite end of the cable.

8. In a device of the class described, a reel freely rotatable on a shaft, manually controlled means to establish a driving connection between the reel and the shaft, a pump, means operable upon rotation of the shaft to establish a driving connection between the reel and the pump and means coupled to the pump outlet to create a progressively increasing back pressure in the pump whereby progressively increasing resistance will be offered to the rotation of the reel, a cable attached at one end to the reel and a grappling hook attached to the opposite end of the cable.

9. In a device of the class described, a reel freely rotatable on a shaft, manually controlled means to establish a driving connection between the reel and the shaft, a pump, means operable upon rotation of the shaft to establish a driving connection between the reel and the pump and an accumulator coupled to the pump outlet to create a progressively increasing back pressure in the pump whereby progressively increasing resistance will be offered to the rotation of the reel, a cable attached at one end to the reel and a grappling hook attached to the opposite end of the cable.

10. In a device of the class described, a reel freely rotatable on a shaft, manually controlled means to establish a driving connection between the reel and the shaft, a pump, means operable upon rotation of the shaft to establish a driving connection between the reel and the pump, a source of fluid supply coupled to the intake side of the pump and an accumulator coupled to the outlet side of the pump to receive the fluid pumped by the pump and create a progressively increasing back pressure in the pump whereby progressively increasing resistance will be offered to the rotation of the reel, a cable attached at one end to the reel and a grappling hook attached to the opposite end of the cable.

11. In a device of the class described, a reel freely rotatable on a shaft, manually controlled means to establish a driving connection between

50

the reel and the shaft, a pump, means operable upon rotation of the shaft to establish a driving connection between the reel and the pump, a source of fluid supply coupled to the intake side of the pump and an accumulator coupled to the outlet side of the pump to receive the fluid pumped by the pump and create a progressively increasing back pressure in the pump whereby progressively increasing resistance will be offered to the rotation of the reel and means to transfer the fluid pumped into the accumulator to the source of fluid supply, a cable attached at one end to the reel and a grappling hook attached to the opposite end of the cable.

15 12. In a device of the class described, a reel freely rotatable on a shaft, manually controlled means to establish a driving connection between the reel and the shaft, a pump, means operable upon rotation of the shaft to establish a driving connection between the reel and the pump, a source of fluid supply coupled to the intake side of the pump and an accumulator coupled to the outlet side of the pump to receive the fluid pumped by the pump and create a progressively increasing back pressure in the pump whereby progressively increasing resistance will be offered to the rotation of the reel and a pump between the accumulator and the source of fluid supply to transfer fluid from the accumulator to said source, a cable attached at one end to the reel and a grappling hook attached to the opposite end of the cable.
